ROCK BIT

Thomas H. Stancliff, Houston, Tex., assignor to
 Reed Roller Bit Company, Houston, Tex., a
 corporation of Texas

Application October 12, 1939, Serial No. 299,069

7 Claims. (Cl. 255—71)

This invention relates to rock bits, and more particularly to those in which the cutter assembly is attached to the bit head by depending legs, and has for its general object the provision of a means for mounting a cutter assembly of this type on a bit head.

In order to provide the necessary rigidity and durability, cutters are usually mounted on shafts which are welded or otherwise permanently secured to the bit head. It is desirable, however, that the cutters be detachable so that they may be readily removed and replaced when worn.

It is an object of this invention therefore to provide a means for securing a cutter assembly to a bit head rigidly yet in a manner which will render it readily detachable.

It is a further object to provide a structure in which the cutters may be first assembled and then detachably secured to the bit head as a unit.

Further objects and features will become evident from the following disclosure, taken in connection with the accompanying drawings, in which—

Figure 1 is a longitudinal cross section of a bit embodying my invention;

Figure 2 is a fragmentary side elevation of the bit shown in Fig. 1, showing the manner of securing the legs supporting the side cutter to the bit head.

Figure 3 is a cross section taken along line 3—3 of Fig. 2;

Figure 4 is a cross-section taken along line 4—4 of Fig. 2;

Figure 5 is a longitudinal cross section of the same bit taken at right angles to Fig. 1.

Figure 6 is a view similar to Fig. 2 showing the manner of securing the legs supporting the cross cutters to the bit head.

Figure 7 is a cross section taken along line 1—1 of Fig. 6; and

Figure 8 is a cross section taken along line 8—8 of Fig. 6.

Referring to the drawings in detail, a bit body 10 has, made integral therewith, the depending tongues 11. These tongues are beveled inwardly on their sides as shown at 12 to provide a dove tail cross section and inwardly and upwardly on their bottom ends as at 13. Above the tongue portions 11 there are formed in the side of the bit body recesses 14, for a purpose to be herein-after explained.

Detachable legs 15 and 15' are formed with bifurcated upper portions forming extensions 16 which form between them dovetail openings or slots narrower at their inner portions than at their outer to receive and conform to the tongues 11, with the beveled portions 12. Likewise, the bottom of each groove is slanted upwardly and inwardly to conform to the bevel portion 13. By these means the legs, when fitted onto the bit,

are securely held against lateral displacement.

Also formed in the sides of the bit body 10 are slots 17, extending below the recesses 14 and transversely of and above the tongues 11. Carried in these slots are bars 18, whose purpose is to assist in holding the legs 15 and 15' in place. This is done by means of bolts or studs 19 in the upper ends of the leg extensions 16, these bolts or studs extending through holes in the bar 18 into the recesses 14. A wrench may be applied to the nuts (or bolt heads) in the recesses 14 to draw the legs 15 up into position and tighten them, thus holding them against longitudinal displacement.

In Figs. 1 to 4, inclusive, the structure of the supporting legs adjacent the side cutters of the bit is illustrated. In these figures the legs 15 are provided adjacent their lower ends with openings 22 which receive the outer ends of a bridge 23 and are welded in place thereon as illustrated in Fig. 1. The bridge 23 is formed just inwardly of its outer ends with suitable bearing recesses for receiving anti-friction bearings 24 and 25 upon which the side cutters 26 are rotatably mounted. These cutters are first mounted on the bridge and the legs 15 are then placed over the ends of the bridge and welded in place thus serving to confine the cutters to their proper position on the bearing portion of the bridge.

The central portion of the bridge is provided with an opening 27 in which is received the inner ends of the cross cutter bearing shafts 28 and 29. These shafts are integral with the legs 15' illustrated in Figs. 5 to 8, inclusive, and their inner ends are secured in position within the opening 27 in the bridge by any suitable means such as by the welding arrangement 30 illustrated in Fig. 5.

The shafts 28 and 29 are provided with recesses adapted to receive suitable radial bearings 31 and 32 and suitable ball thrust bearings 33 and 34 which provide for the rotatable support of the cross roller cutters 21.

In assembling the device just described, the side cutters 26 are mounted upon the ends of the bridge in the position illustrated and after the proper anti-friction bearings 24 and 25 have been put in place, the legs 15 are placed over the ends of the bearing portions of the bridge and welded in place as shown. The cross roller cutters 21 are placed over their respective stud shafts on 30 the arms 15' with the anti-friction bearings illustrated in their proper position therein. The inner ends of these stud shafts are then inserted into the bridge and welded in position, as shown at 30. The unit as a whole may then be moved on 35 to the shank or head portion of the bit 10 and the extensions of the respective arms 15 and 15' are engaged with the dovetail tongues 11 on the body. The studs and bolts 19 are then put into position and tightened so as to draw the entire unit

firmly into engagement with the bit head. In the showing in Fig. 2, studs 19 are provided with nuts 20 for holding and tightening them, whereas, in Fig. 6, the bolts 19' have their heads disposed within the recesses 14 and are available for tightening for this purpose.

By the structure set out above, I have produced a rock bit with a cutter assembly which is detachable and replaceable in a highly efficient manner, so that, when a cutter or cutters become worn out or damaged, this cutter or the entire cutter assembly may be changed and the entire bit need not be replaced. I do not wish to be limited to the specific embodiments disclosed herein, but only by the scope of the appended claims.

I claim:

1. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, said side faces co-

25 operating with said tongue members to rigidly secure said detachable legs on the bit head against lateral displacement, and means for holding said legs against longitudinal displacement.

2. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, said side faces cooperating with said tongue members to rigidly secure said detachable legs on the bit head against lateral displacement, the bottom end surfaces of each of said tongue members being inclined downwardly and outwardly relative to said bit head axis and their inner ends stopping abruptly at a vertical shoulder on each of said tongue members to assist in preventing lateral displacement, and means for holding said legs against longitudinal displacement.

3. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, cutter means held between the legs, said side faces cooperating with said tongue members to rigidly secure said detachable legs on the bit head against lateral displacement, and means for holding said legs against longitudinal displacement.

4. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, cutter means held between the legs, said side faces cooperating with said tongue members to rigidly secure said detachable legs on the bit head against lateral displacement, the bottom end surfaces of each of said tongue members being inclined downwardly and outwardly relative to said bit head axis and their inner ends stopping abruptly at a vertical shoulder

on each of said tongue members to assist in preventing lateral displacement, and means for holding said legs against longitudinal displacement.

5. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, cutter means journaled between the legs, said side faces cooperating with said tongue members to rigidly secure said detachable legs on the bit head against lateral displacement, the bottom end surfaces of each of said tongue members being inclined downwardly and outwardly relative to said bit head axis and their inner ends stopping abruptly at a vertical shoulder on each of said tongue members to assist in preventing lateral displacement, transverse slots and recesses in said bit head above said tongues, bars in the slots, bolt means for holding the legs on said bit head, said bolt means extending through said bars and having parts in said recesses whereby they may be tightened.

6. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, apertures in the bottom ends of said legs, a cutter shaft mounted in each of said apertures, said side faces cooperating with said tongue members to rigidly secure said detachable legs on the bit head against lateral displacement, the bottom end surfaces of each of said tongue members being inclined downwardly and outwardly relative to said bit head axis and their inner ends stopping abruptly at a vertical shoulder on each of said tongue members to assist in preventing lateral displacement, transverse slots and recesses in said bit head above said tongues, bars in the slots, and means for holding said legs on said bit head, said means comprising bolts extending from the upper ends of the legs through the bars into the recesses, and lock nuts on the bolts in the recesses.

7. In a rock bit, a bit head having a plurality of integral tongue members extending outwardly from vertical side faces on said bit head, said tongue members having wedge-shaped outer portions which taper inwardly relative to the bit head axis, detachable legs having slots therein fitted on said tongue members, stub shafts on the bottom ends of said legs, a cutter assembly journaled on said stub shafts, said side faces cooperating with said tongue members to rigidly secure said detachable legs on the bit head against lateral displacement, the bottom end surfaces of each of said tongue members being inclined downwardly and outwardly relative to said bit head axis and their inner ends stopping abruptly at a vertical shoulder on each of said tongue members to assist in preventing lateral displacement, transverse slots and recesses in said bit head above said tongues, bars in the slots and means for holding said legs on said bit head, said means consisting of threaded holes in the upper ends of the legs and bolts, with their heads in said recesses, extending through the bars and into the threaded holes.

THOMAS H. STANCLIFF.
